DOOR MOUNTING

Arthur I. Epton and Max W. Feldman, Chicago,
Ill.

Application May 19, 1930. Serial No. 453,460

5 Claims. (Cl. 16—147)

This invention relates to certain novel improvements in door mountings and has for its principal object the provision of an improved construction of this character which will be highly efficient in use and economical in manufacture.

The present invention constitutes an improvement over the invention disclosed in the application filed by William P. Huebner, on or about March 28, 1930, Ser. No. 439,763, for Letters Patent on a Door mounting.

Among the salient objects of this invention is to provide a door mounting which will permit the door to be opened from either of the side jambs of the door openings and wherein the door mounting is of such arrangement that should, by accident or negligence, one side of the door mounting not be completely disposed in an operative position upon opening of the opposite side the door will be retained in position thereby preventing the door from accidentally being displaced from its mountings completely.

A still further object of the invention is to provide a hinge structure for a door, window, or other closure member for an opening whereby one unit of the hinge structure may be completely detached from the other unit of the hinge structure by pulling pressure applied to the one hinge structure.

Other objects will appear hereinafter.

30 The invention consists in the novel combination and arrangement of parts to be hereinafter described and claimed.

The invention will be best understood by reference to the accompanying drawing, showing the preferred form of construction and in which:

Fig. 1 is an elevational view of a door opening, showing a door associated therewith with our improved door mounting connected thereto;

Fig. 2 is a sectional detail view taken substantially on the line 2—2 of Fig. 1;

Fig. 3 is a perspective view of a hinge unit showing the parts thereof in disconnected position;

Fig. 4 is a sectional detail view taken substantially on the line 4—4 of Fig. 1;

Fig. 5 is a perspective view of the parts illustrated in Fig. 4, showing the same in disconnected position; and

Fig. 6 is a sectional detail view showing the door in a partially dislocated position with respect to the door opening and casing of said opening.

In the use of our invention, it is understood that our improved door mounting may be associated

with a closure member for closing an opening of any structure.

In the drawing, a casing is indicated at 10 and this casing defines an opening 11. Associated with this casing to close the opening 11 is a closure member 12, which we prefer to term herein as a "door". With this casing and door is associated our improved door mounting 13 and door latch structures 14, each of which will be now described in detail. Each of the door mountings 13 are substantially similar in construction and, therefore, the description herein will be equally applicable to any one of the door mountings 13.

In the present instance our improved door mounting includes a hinge structure generically indicated at 15. This hinge structure includes hinge leaves 16 and 17.

The hinge leaf 17 includes a body plate 18 and a knuckle 19 which is preferably formed as an integral part of the body plate 18. Provided in the body plate 18 are openings 20 through which project the connecting screws 21 whereby the hinge leaf 17 is connected to the door 12.

The knuckle 19, as shown, includes a relatively wide plate 22 bifurcated to provide oppositely disposed fingers 23 defining a slot 24.

The hinge leaf 16 includes a body plate 25 providing oppositely disposed knuckles 26 arranged in spaced relation with respect to each other and joined together on one side by a plate 27 formed integral with the knuckles as shown. The outer edge 28 of this plate extends outwardly from the body plate 16 to a point outwardly of the longitudinal axis of a pintle 29 carried between the knuckles as shown. The body plate 25 is provided with openings 30 for the projection of connecting screws 31 whereby to effectuate connection between this hinge leaf and the casing 10.

Referring again to the hinge leaf 17, there is provided in the knuckle 19 thereof a bore 32 terminating at its inner end portion with a reduced opening 33 which opens into the slot 24. Slidably mounted in this opening 33 is a head bearing latch pin 34, the inner end portion of which is beveled as at 35 for reasons hereinafter understood.

Bearing against the head of the pin 34 is a spring 36 arranged in the bore 32 and compressed against this head by means of a set screw 37. By adjusting the head screw 37 the tension of the spring may be readily regulated.

From the description set forth relative to the hinge leaf 16 it will be seen that by the relative position and design of the knuckles 26 and plate

27 that a relatively deep socket is provided to receive the fingers 23 for accomplishing the purpose herein set forth.

Referring now to Figs. 4 and 5, the latch structures 14 each include a body plate 38 having suitable openings 39 formed therein for the passage of connecting screws 40 whereby to effectuate connection between the body plate and the door 12. This body plate provides a housing 41 and 10 slidably arranged in the housing 41 is a bolt 42 having a reduced cylindrical stem 43 projecting through an opening 44 formed in the housing 41. The bolt is urged in an outer position by means of a spring 45 arranged in the housing between 15 a wall thereof and the bolt 42. The bolt has one end extending exteriorly of the housing and this end provides a latch head 46, which latch head includes a notch 47 adapted to receive the pintle 48 carried by a keeper plate 49. This keeper plate 49 includes spaced knuckles 50 between which is arranged the pin 48 and these knuckles are likewise connected together at one side by means of a plate 52 similar to the plate 27.

The bolt 42 includes a transverse opening 53 and projecting into this opening for engagement with the bolt is a pin or lug 54 which is formed as an integral part of an operating handle 55 pivotally supported between suitable bearings 56 carrying a pintle 57 projected through the operating handle as shown.

As indicated herein, by the use of door mountings constructed in accordance with the description herein the door may be opened from either of the side jambs and this is accomplished in the following manner. To open the door from the left hand jamb the operating handle of the latch structure indicated at "A" is manipulated in a direction to slide the bolt 42 against the action of the spring 45 whereby to disengage the latch notch from engagement with the pin 48. Now by applying outward pulling pressure on the handle the door will swing upon the door mountings on the left hand side. The door may be closed in the usual manner by applying pressure to the door in closing direction. Assuming that by negligence or by accident the door is not completely closed but that the fingers of the door mountings on the left side are in close proximity with the pins of the hinge leaf 16 on this side of the door, but not in proper engagement so as to complete a connection. If the operator grasps the operating handle of the latch structure on the right hand side of the door and manipulates this handle in a direction to disengage the latch head from its pintle on this side of the door it is obvious that unless some means is provided that the door will completely drop from position in the door opening and probably injure the operator or otherwise create damage. When this condition exists it is pointed out that as soon as the operator applies pressure to the right hand side of the door the door will move a very short distance, which distance is not sufficient to disengage the fingers from confinement between the knuckles 26 and the plate 27 because at this point the weight of the door, as shown in Fig. 6, will be transposed to both or one of the door mountings on the right hand side and consequently the fingers will wedge between the knuckles 26 and against the plate 27. Lateral movement of the door under these conditions is prevented by reason of the fact that the plate 27 has its edge 28 disposed sufficiently far enough beyond the longitudinal axis of the pin 29 and consequently complete disconnection between the fingers and

the hinge leaf 16 is prevented. It will thus be seen that the door cannot drop from its position in the opening beyond a point where the wedging effect takes place between the fingers and the knuckles 26 and plate 27. Therefore, if the door is inadvertently left partially open at one side the opening action of the door from the other side will attract attention to that effect and consequently injury to the operator is prevented and complete disassembly of the door averted.

While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention what we claim as new and desire to protect by Letters Patent is:

1. In a mounting of the class described, a hinge leaf providing a knuckle having a bifurcated portion extending therefrom at substantially right-angles with respect to the body portion of the leaf, a second hinge leaf providing portions providing a relatively deep socket to receive said extended portions, and a member positioned transversely in the socket in the path of the bifurcation of said portion of said knuckle.

2. A mounting of the class described including a hinge leaf providing a body plate, a knuckle provided by the body plate and having a relatively wide portion formed thereon and extending at rightangles with respect to the body plate and slotted to provide opposite fingers, a second hinge leaf having a lateral portion providing a relatively deep socket to receive said fingers, and a member extending transversely of the socket and adapted to fit into said slot, said fingers being adapted when said first mentioned hinge leaf has a weight disposed thereon to wedge against portions of said lateral portions within said socket.

3. In a mounting of the class described, a pair of hinge leaves, one of said leaves being provided with a bifurcated portion and the other of said leaves being provided with a socket adapted to receive the bifurcated portion, a member positioned transversely in the socket in the path of the bifurcation of said bifurcated portion, and means for effectuating detachable connection between said hinge leaves, said means including an element movable automatically by engagement with the said member when said hinge leaves are moved from and to connected position.

4. In a mounting of the class described, a hinge leaf providing a knuckle having a bifurcated portion extending therefrom at substantially right-angles with respect to the body portion of the leaf, a second hinge leaf providing portions providing a relatively deep socket to receive said extended portions, a member positioned transversely in the socket in the path of the bifurcation of said portion of said knuckle, and spring urged means for effecting detachable connection between said first mentioned hinge leaf and said second mentioned hinge leaf, said spring urged means being operable to permit detachment of said hinge leaves by pressure of said pintle against an element of said means.

5. A mounting of the class described including a hinge leaf providing a body plate, a knuckle provided by the body plate and having a rela-

tively wide portion formed thereon and extending at right-angles with respect to the body plate and slotted to provide opposite fingers, a second hinge leaf having a lateral portion providing a 5 relatively deep socket to receive said fingers, a member extending transversely of the socket and adapted to fit into said slot, said fingers being adapted when said first mentioned hinge leaf

has a weight disposed thereon to wedge against portions of said lateral portions within said socket, and means adapted to co-operate with said member to effectuate automatic separation and connection between said first mentioned hinge leaf and said second mentioned hinge leaf
